AIRPLANE BOX KITE

Curtiss J. McCoy, Indianapolis, Ind.

Application October 23, 1947, Serial No. 781,679

3 Claims. (Cl. 244—154)

1

This invention relates to an airplane box kite. The chief object is to provide a box kite of airplane type which is comprised of but few parts and these of such material and size that in and of themselves they individually have but little structural strength and are of such size that they can be included as a premium in a carton having at least one dimension or diagonal but slightly larger than half the wing span.

The chief feature of the present invention resides in the construction of a box kite in airplane form and of parts having the characteristics aforesaid.

Other objects and features of the invention will be set forth more fully hereinafter.

The full nature of the invention will be understood from the accompanying drawings and the following description and claims:

In the drawing Fig. 1 is a plan view of parts in disassembled relation.

Fig. 2 is a front elevational view.

Fig. 3 is a top plan view.

Fig. 4 is a side elevational view.

Fig. 5 is a transverse sectional view taken on line 5—5 of Fig. 3 and in the direction of the arrows.

Fig. 6 is a transverse sectional view taken on line 6—6 of Fig. 4 and in the direction of the arrows.

In Fig. 1 there is illustrated a wing outlined sheet of paper 10, of the character generally used for labels. Obviously it is very light and fairly tough and may be colored on either or both sides as desired. 11 indicates a strip of similar paper for forming the forward cell of the kite. It may have the same or a contrasting color. 12 indicates a strip of similar paper for forming the trailing cell, it being understood that the resulting box flies with the cells more or less one behind the other, thus differentiating from a conventional box kite. Strip 12 may be of the same color as the forward cell strip or that of the wing if of contrasting color.

13 indicates a sheet of heavier paper, such as 110 pound, and 14 another sheet of the same type paper board. The smaller dimension thereof may be optional. 15 indicates five substantially identical sticks of a length approximately half the span of the wing. 9 indicates an optional horizontal elevator member of the same weight as sheets 13 and 14. Herein for tail skid representation sheet 12 at opposite ends terminates in ogee curve formations. This is optional.

Reference will now be had to Figs. 2 to 6 in-

2

clusive wherein the aforesaid parts are illustrated in assembled relation, it being understood that the horizontal stabilizer and vertical stabilizer (rudder) can be omitted in the simpler forms of the basic invention, and in the simplest form both stabilizers are omitted.

Secured to the forward edge of sheet 13 and in longitudinal alignment and preferably in end to end engagement are two of the balsa wood sticks 15. In parallel relation are two other sticks 15 with their ends abutting the first mentioned sticks. The latter two sticks are secured to the two sides immediately contiguous to the first mentioned side of sheet 13.

15 The end-to-end wing stick engagement is medianly disposed relative to said first mentioned side. To the four adjacent end portions of said four sticks and to the sides opposite those adhesively secured to said sticks there is adhesively secured sheet 14.

15 The sheet 10 (the wing) is then adhesively secured to sheet 13 and to the exposed faces of the aligned sticks 15 so that the former is stiffened. The result is a relatively rigid wing structure, the forward edge of which is rigid, by reason of the aligned sticks 15, and the central portion of which is stiffened and stabilized by sheets 13 and 14 and the rearwardly directed parallel sticks 15.

30 Sheet 11 is scored or creased as at 16 and 17, the latter forming flaps 18 and the former sides 19 and central portion 20. Each flap 18 is apertured at 21. Said flaps are adhesively secured together after portions 19 and 20 are disposed 35 in triangular relation. This disposes the double flap structure outwardly and perpendicularly to side 20.

Side 20 is then adhesively secured to the free surface of wing 10 and when so secured crease 40 lines 16 register with the outside faces of the two parallel sticks and the edge of portion 20, closest to holes 21, registers with the forward edge of wing 10 and the two forward faces of the aligned sticks 15. This is a further reenforcement for the central portion of the wing. Holes 21 now register and are located at the forward portion of the forward cell, and flaps 18 serve as a vertical vane in flying.

Sheet 12 is then folded into triangular form on score or crease lines 22 and 23 which form adjacent sides 24 and central portion 25 and the end flaps 26. For convenience only strips 11 and 12 may have the same width. They are 55 dissimilar in length. The two flaps 26 with tail

skid ogee outline 26^a are adhesively secured together forming the rear or trailing cell.

The free ends of the two parallel sticks on the outermost sides and the coplanar sides substantially coincident with strip 14, or the sides to which said strip is secured, are then provided with adhesive and inserted into the rear cell and secured at the two corners substantially in alignment with the wing. Thus the tail skid portion, if provided, is medianly and dependingly disposed relative to lower rear end of the airplane box kite.

Then the remaining stick has adhesive applied to the same and two adjacent faces at opposite ends and inserted into the two cells at the depending vertices thereof so that it is coextensive with the creases 17 and coextensive with creases 22 to approximately the same extent as the two parallel sticks 15 are coextensive with creases 23.

There is a slight difference since the end of the lower stick extends forwardly of the ends of the upper parallel sticks by the width of the wing aligned sticks 15. Preferably but not necessarily the rear cell receives the projecting ends of the triangularly disposed parallel sticks to an extent equal to about one half the length of said cell.

Also by reason of the forward cell not enveloping, as it were, the two parallel sticks while the rear cell does, the lengths of comparable portions 20 and 25 and 19 and 24 are not equal.

Whenever a tail skid is not desired one flap 26 may have the shape of a flap 18 and be an extension of one side and lap the other side 24 and be adhesively secured thereto.

Furthermore, the airplane box kite of either form, that is, with or without the tail skid, may have secured to it the horizontal stabilizer sheet 9 as by gluing the central portion thereof to portion 25 of the rear cell and in the desired relationship. Herein it is illustrated as disposed rearwardly thereon, see Figs. 3 and 4.

While the invention has been illustrated and described in great detail in the drawings and foregoing description, the same is to be considered as illustrative and not restrictive in character.

The several modifications described herein as

well as others which will readily suggest themselves to persons skilled in this art, all are considered to be within the broad scope of the invention, reference being had to the appended claims.

The invention claimed is:

1. An airplane box kite including in combination a forward triangular outlined cell, a similar rearward triangular outlined cell, the same being directed downwardly, stick members connecting same in spaced relation and disposed at the vertices of said cells, and oppositely directed wings juxtaposed to the forward cell, each wing having a trailing and a leading edge, one of said edges of each wing substantially straight, the straight edges being longitudinally aligned, a stick member registering with and secured to that straight edge and having its end adjacent the cell secured to one side of that cell, and vertical and horizontal stabilizing vane means carried by the rearward cell.

2. An airplane box kite as defined by claim 1 wherein the vertex disposed and wing edge disposed stick members are substantially of equal length.

3. An airplane box kite as defined by claim 1 wherein the edge disposed stick members substantially abut at their adjacent ends, and a pair of reinforcing sheets disposed in parallel relation with the abutting ends of the stick members secured therebetween, one of said reinforcing sheets being substantially coextensive in length with the width of a face of the forward cell and secured thereto.

CURTISS J. McCOY.
